NECKTIE FINISHER

Clifford C. Palmatier and Fredrick L. Wehren,
Bozeman, Mont.

Application May 19, 1950, Serial No. 162,924

7 Claims. (Cl. 223—82)

1 This invention relates to a necktie finisher. Numerous efforts have been made to provide devices for pressing or finishing neckties, particularly in cleaning and pressing establishments. These devices largely have failed to accomplish their desired functions for one or more of several reasons. For example, many of such devices are relatively expensive to build, but most of them fail for the reason that they are inoperative for providing a satisfactorily finished necktie. The reason for this usually is because of the fact that devices of this character usually are steam operated, and wet steam is supplied to the necktie for the finishing operation, which results in the spotting or streaking of the tie. Most of these devices likewise fail for the reason that they do not have means which efficiently operate to hold the necktie on the forming element used in the finishing operation.

An important object of the present invention is to provide a simple and novel type of necktie finisher, wherein a necktie may be very quickly and easily finished to present the appearance of a new tie without any spotting or streaking of the fabric or any of its colors.

A further object is to provide a device of this character which is so constructed as to be connectible to any suitable source of steam, as is available in all cleaning and pressing establishments, and wherein only dry steam is supplied to the face of the tie with the result that there is no streaking or spotting of the tie.

A further object is to provide a device of this character employing a novel type of necktie former having a novel steam supply means together with novel means for maintaining in dry condition the steam which is fed to the necktie.

A further object is to provide a novel former in a necktie finisher wherein a steam conduit is used in the former for supplying steam to the necktie and wherein such conduit is surrounded by steam which does not come into contact with the tie but which maintains the conduit in a heated condition to prevent a condensation of steam therein whereby only dry steam is supplied to the necktie.

A further object is to provide novel means for trapping in the supply line to the live steam conduit any minor amount of condensation which may collect in such line.

A further object is to provide novel steam supply means of such character that substantially nothing but dry steam is allowed to reach the dry steam conduit.

A further object is to provide a novel type of

2 clamp engageable with the back of the tie to hold it in position during the finishing operation, thus preventing the tie from creeping upwardly along the tapered former without the necessity for having to hold the tie in position with the hands or fingers.

Other objects and advantages of the present invention will become apparent during the course of the following description.

10 In the drawing, we have shown one embodiment of the invention. In this showing,

Figure 1 is a perspective view of the apparatus, parts being broken away,

15 Figure 2 is a transverse sectional view through the former taken substantially on line 2—2 of Figure 1, and

Figure 3 is a fragmentary vertical sectional view on line 3—3 of Figure 1.

Referring to Figure 1, the numeral 10 designates a structural surface which may be a table or counter top, or the top of a cabinet in which may be housed the steam supply means described below. Beneath the top 10 is arranged the means for supplying steam to the necktie

25 former to be described. The steam supply means comprises a vertical tank 11 intermediate the ends of which is connected a steam supply pipe 12 leading to any suitable source of steam, such as the steam boilers customarily employed in cleaning and pressing establishments. This pipe is preferably provided with a manually operable cut-off valve 13. The tank 11 is provided with two outlet pipes 14 and 15, the respective purposes of which will be described in detail below.

30 Particular attention is invited to the fact that the pipe 14 is connected to the tank 11 near the top thereof, while the pipe 15 is connected to the tank 11 at a point spaced from the top of the tank, for example, near the bottom of the tank as shown in Figure 1. The bottom of the tank is provided with a condensation drain pipe 16 in which is arranged a manually controllable valve 17.

35 Above the top 10 is arranged a necktie former indicated as a whole by the numeral 20. This former has a somewhat curved forward wall 21 and a preferably flat rear wall 22 as clearly shown in Figure 2. The former 20 is tapered to decrease in size upwardly approximating the

40 taper of the ends of a necktie. The pipe 15 leads to the interior of the former 20 to discharge steam into the space 24 therein. Since the interior of the former is subjected to substantial steam pressure, the forward and rear

45 walls are connected by stays 25, preferably

3

welded in position to serve as braces between the forward and rear walls 21 and 22. The former 20 is preferably covered by a light porous fabric 28 such as cotton drilling or the like.

A live steam conduit 30 extends vertically through the former. This conduit is substantially semi-circular in cross section as shown in Figure 2 with the edges thereof welded to the front wall 21 of the former and with the back of the member 30 spaced from the back wall 22 so that the space 24 will be continuous throughout the width of the former to allow steam from the pipe 15 freely to reach all portions of the interior of the former except the space 31 within the conduit 30.

The conduit 30 is arranged centrally of the width of the former and the front wall 21 is provided with spaced discharge openings 32 for the escape of the steam from the space 31 through the fabric covering 28, if the latter is employed, and then through a necktie arranged on the former. Particular attention is invited to the fact that none of the steam in the space 24 is ever discharged through the former, but merely acts to maintain in highly heated condition the steam within the space 31.

Steam is supplied to the conduit 30 from pipe 14 in the manner shown in detail in Figure 3. This pipe is threaded into the bottom wall 34 of the former and within the upper end of the pipe 14 and preferably welded in position is a bushing 35 having an axial steam passage 36 therethrough. The lower end of the bushing 35 is preferably hemispherical as at 37 for a purpose to be described. At a convenient point therein, the pipe 14 is provided with a novel cut-off valve 40 of the conventional spring-closing type. Inasmuch as any number of types of such valves are commercially available, the valve 40 need not be shown in detail. This valve is operable by a depending stem 41 which may be suitably guided by any desired means (not shown) and is provided at its lower end with an operating treadle 42.

Means are provided for clamping a necktie in position on the former to hold it in a fixed position during the finishing operation without the use of the hands. Such means comprise a relatively rigid clamping plate 45 generally corresponding in shape to the back wall 22 and formed flat to engage thereagainst. At its edges, the clamping plate is provided with turned flanges 46 adapted to lie along the edges of the former, these edges being slightly rounded as at 47 (Figure 2). The clamping plate 45 is fixed to the upper end of a spring leaf 48, the lower end of which is welded or otherwise fixed to a lever 49, pivotally supported at its lower end as at 50 on the top 10. The lever operates adjacent a toothed quadrant 51 fixed to the top 10, and a detent 52 is engageable with the teeth 53 of the quadrant. The detent 52 is urged upwardly by any suitable means and is moved downwardly to disengage it from the quadrant teeth by depressing a button 54. Since the quadrant and detent means per se are old and well known in the art, it is believed that they need not be illustrated in detail.

Operation

When it is desired to finish a necktie on the apparatus, the end of the necktie is slipped downwardly over the former until it fits snugly thereon. The operator then moves the lever 49 forwardly to engage the plate 45 against the back of the former, the plate 45 being

held in position under the tension of the spring 48 and the lever being locked in position by the detent 52 engaging one of the teeth 53. Assuming that the valve 13 is opened, steam will be maintained in the tank 11 and will flow through the pipe 15 into the former space 24 to maintain the former in a heated condition. The operator will now depress the treadle 42 to open the valve 40 and admit steam from tank 11 through pipe 14 into the conduit space 31, steam flowing from this space through openings 32, thence through the fabric cover 28, if this is employed, and thence through the necktie. It has been found that only a single central line of openings 32 need be employed to supply sufficient steam to the necktie to effect an excellent finishing operation thereon. After the finishing operation has been completed, the operator will press the button 54 to release the detent mechanism and permit the clamping plate 45 to move back to inoperative position, for example, as shown in Figure 1. The finished tie then may be slipped from the upper end of the former.

The apparatus embodies several features which combine to provide a highly efficient necktie finishing operation. The steam is supplied to the tank 11 and wet steam and condensation tend by gravity to move toward the bottom of the tank, thus leaving drier steam near the top of the tank. It is this dry steam which is supplied to the conduit 30 through the pipe 14, and any condensation on the sides of the pipe 14 will be trapped at the bushing 35. The flow of steam through the axial passage 36 does not tend to carry with it any condensation since the latter collects around the outside of the hemispherical face 37. Thus the device tends to provide solely dry steam for the finishing operation.

The operation of the apparatus is not affected in any way if wet steam is supplied through pipe 15 to the space 24. This steam does not come in contact with the necktie but merely serves to maintain the conduit highly heated to eliminate or very substantially minimize any condensation within the dry steam conduit. Thus the heating of the space 24 and conduit 30 functions to prevent the supplying of any but dry steam to the necktie. It has been found that an excellent finishing operation on the necktie may be provided with dry steam, whereas moist steam or condensation tend to streak or spot the tie, this being particularly noticeable on neckties having bright colors therein. The present device accordingly is highly efficient as a necktie finisher.

It has been found that neckties tend to creep from formers of this type, thus making it necessary ordinarily to hold the tie on the former by the hands of the operator. By clamping the plate 45 against the flat rear face of the former under spring tension, the necktie during the finishing operation is fixedly held in position against creeping and it is not necessary for the operator to touch the necktie with his hands or fingers during such time, thus eliminating a cause of the spotting of neckties being finished. The clamping plate is instantly moved to operative position and holds itself in position without attention by the operator, and is instantly released by pressing the button 54.

Obviously the space 24 is maintained during normal operation under static steam pressure, and accordingly condensation within the space 24 flows downwardly through pipe 15 back into the bottom of the tank 11. Some condensation in time will form in the pipe 14, but this conden-

sation is very slight in quantity. From time to time, the operator may close the valve 13, open the valve 17 and hold the treadle 42 depressed. This will drain condensation from the tank 11 and also will permit any condensation which may have occurred in the pipe 14 to flow back into the tank 11 to be discharged through pipe 16. After the pipes and the tank 11 have been drained, it merely is necessary to close the valve 17 and open the valve 13, whereupon the apparatus is again ready for use.

In practice, it has been found that the present device provides a cleaned and finished necktie with a new tie appearance. The rounded edges 47 leave the edges of the necktie slightly rounded as in the case of a new tie, and the functioning of the device is such that the colors of the tie will appear clean and fresh with a complete absence of any spots or streaks.

We claim:

1. A necktie finishing device comprising a hollow elongated former over which one end of a necktie is adapted to be placed, an elongated conduit in said former closed to the interior thereof, means for supplying steam to said conduit, one wall of said former having apertures therein communicating solely with said conduit for the escape of steam from said conduit through the necktie, and means for heating the interior of said former for minimizing the condensation of steam in said conduit.

2. A necktie finishing device comprising a hollow elongated former over which one end of a necktie is adapted to be placed, an elongated conduit in said former closed to the interior thereof, means for supplying steam to said conduit, one wall of said former having apertures therein communicating solely with said conduit for the escape of steam from said conduit through the necktie, and means for supplying steam to the interior of said former to heat said conduit and minimize the condensation of steam therein.

3. A necktie finishing device comprising a hollow elongated former over which one end of a necktie is adapted to be placed, an elongated conduit in said former, a steam pipe for supplying steam to said conduit, said former having walls one of which has perforations communicating with said conduit for the escape of steam therefrom, a bushing in said steam pipe having a reduced axial passage therethrough for the flow of steam, the end of said bushing remote from said conduit being hemispherical to provide for the trapping of condensation around such end of said bushing, and means for heating the interior of said former to heat said conduit and minimize the condensation of the steam therein.

4. A necktie finishing device comprising a hollow elongated former over which one end of a necktie is adapted to be placed, an elongated conduit in said former, a steam pipe for supplying steam to said conduit, said former having walls one of which has perforations communicating with said conduit for the escape of steam therefrom and said wall being otherwise imperforate, a bushing in said steam pipe having a reduced axial passage therethrough for the flow of steam, the end of said bushing remote from said conduit being hemispherical to provide for the trapping of condensation around

such end of said bushing, and means for supplying steam to the interior of said former around said conduit to heat the latter and minimize the condensation of steam therein.

5. A necktie finishing device comprising a hollow elongated former over which one end of a necktie is adapted to be placed, an elongated conduit in said former, one wall of said former being provided with apertures therethrough communicating at their inner ends solely with said conduit, a steam tank, means for supplying steam to said tank, a steam pipe connected between said conduit and the top of said tank to supply relatively dry steam from said tank to said conduit for discharge through said apertures, said steam pipe having a vertical portion, and a bushing therein having a reduced axial passage therethrough and provided with a substantially hemispherical lower end.

20 6. A necktie finishing device comprising a hollow elongated former over which one end of a necktie is adapted to be placed, an elongated conduit in said former, one wall of said former being provided with apertures therethrough communicating at their inner ends solely with said conduit, a steam tank, means for supplying steam to said tank, a steam pipe connected between said conduit and the top of said tank to supply relatively dry steam from said tank to said conduit for discharge through said apertures, said steam pipe having a vertical portion, a bushing therein having a reduced axial passage therethrough and provided with a substantially hemispherical lower end, and a pipe connected between the interior of said former and said steam tank at a point spaced from the top of the latter to supply steam to the interior of said former to heat said former and said conduit to minimize condensation of steam in said conduit.

30 7. A necktie finishing device comprising a hollow elongated former, said former having walls one of which is provided with a plurality of longitudinally spaced perforations, a member of open section arranged in said former and having its edge portions fixed in sealed relation to said one wall on opposite sides of said perforations to form therewith a steam conduit communicating with said perforations but closed off from the interior of said former, said walls outwardly of said conduit being imperforate, means for admitting steam to said conduit for escape through said perforations, and means for admitting steam to the interior of said former around said conduit to heat the latter and minimize the condensation of steam therein.
